DEFLECTOR FOR CLOSE COUPLED OIL
BURNERS

Robert F. Andler, Rutherford, and Louis W. Schroeder, Passaic, N. J., assignors to Electrol Incorporated, Clifton, N. J., a corporation of Delaware

Application July 20, 1937, Serial No. 154,549

5 Claims. (Cl. 158—1.5)

Our invention relates to the type of oil burner known to the trade as the ball flame and is especially intended to meet conditions which the deflector described in our copending application 5 Serial No. 154,548 of even date herewith will not take care of. Practice has shown that that deflector functions perfectly where the burner has a rated capacity of about three gallons per hour, or, as expressed in the trade, 3 G. P. H.; but with 10 an 8 G. P. H. burner, which requires the provision of about 2½ times as much air to burn the oil, the air stream leaving the fan does not rotate around the scroll case as it will in the burner described in our said copending application. 15 Even if a deflector like that disclosed in the construction of our copending Patent No. 2,197,912, April 23, 1940, were used, although in practice it produced a symmetrical fire, it was impractical because it reduced the area so much 20 proper air capacity could not be attained.

Our invention has for its principal object to produce a deflector through the use of which all the foregoing difficulties are overcome and an 25 8 G. P. H. burner can be produced without destroying in the least the fire symmetry or the proper combustion which is essential to a satisfactory oil burner.

Our means of accomplishing the foregoing objects may be more fully comprehended by having 30 reference to the accompanying drawings, hereunto annexed and made a part of this specification, in which:

Fig. 1 is a front elevation of an oil burner employing our improved deflector, a portion being shown in section;

Fig. 2 is a side elevation of the same;

Fig. 3 is a detailed plan view of the scroll case and part of the blast tube, the scroll case being partly broken away to show the deflector in position;

Fig. 4 is a detail view of scroll case and blast tube partly in section showing our deflector in end elevation;

Fig. 5 is a detail view of the scroll case and blast tube showing in dotted lines our deflector in side elevation;

Fig. 6 is a perspective view of the deflector showing the air inlet end; and

Fig. 7 is a perspective view of the deflector showing the face for guiding the air stream.

Similar reference numerals refer to similar parts throughout the entire specification.

In the drawings which show a close coupled oil burner of standard type, we provide an electric motor 1 which is directly connected to a

blower fan 2 of standard type and which is arranged to discharge air tangentially into a member 13 which in the trade is called the scroll case. From one side of this scroll case 13 extends a tube 4 which in the trade is called a blast tube. 5 As in standard practice, an oil pipe which terminates in a nozzle 5 is mounted in the blast tube. The nozzle 5 is located adjacent the combustion chamber (not shown). The foregoing parts being of more or less standard construction are illustrated diagrammatically. Our invention, i. e., a deflector 15 for use in such an oil burner is shown clearly in perspective Figs. 6 and 7, and in position for use inside the scroll case 13 and adjacent the discharge port 3 of the fan in the 15 other views.

The deflector 15 is generally wedge-shaped in form. Its lateral or side surfaces (assuming the deflector to be in its proper position in the scroll case, as shown in Figs. 1 and 2), designated as 20 9 and 11, are plane surfaces angularly disposed to each other. The upper surface 8 and lower surface 14 are cylindrical and extend at right angles to surface 11. The radius of surface 8 is that of the scroll case 13, while the radius of 25 surface 14 is greater than that of the blast tube 4.

The several surfaces converge at one end of the deflector to form the common point 10, and surfaces 8 and 11 would, if uninterrupted, converge on a line at the opposite end; however, 30 this end is cut away to form a cylindrical surface 7, having a radius equal to that of the discharge opening 3 from the fan 2, and two points or extensions 6 and 12.

It is to be noted that surface 9 is longer than 35 surface 11, and that the entire deflector extends throughout an arc less than 180° within the scroll case 13.

The deflector 15 is mounted in the scroll case 13 with its upper surface 8 in contact with the 40 inner face of the scroll case rim and its side surface 11 in contact with the inner face of the side of the scroll case opposite the blast tube 4, as shown in Fig. 3. The surface 7 is adjusted to coincide with and form a continuation of the 45 discharge opening 3.

With the deflector 15 so mounted the stream of air issuing from port 3 is prevented from passing directly into the blast tube 4, and is forced to take a circular course within the scroll 50 case 13. Before completing a full circle within the scroll case, however, the air stream encounters the surface 9, angularly disposed within the case, and its rotation is reduced and its course deflected into the blast tube 4.

By adjusting the angular relationship of the surface 9 to the surfaces 8 and 14, the degree of rotation of air within the blast tube 4, and hence the flame characteristics can be closely controlled, and a "ball-shaped" flame of desired diameter obtained.

It will be appreciated that the term "upper" is used herein with reference to that portion of the scroll case at which the air stream from the blower enters, and that with installations in positions other than that shown in Figs. 1 and 2, such portion may not in fact be uppermost. The term "upper" and other corresponding terms as used herein are not, therefore, to be limited to their literal significance, but refer broadly to functional directions with reference to the direction of entry of the air stream into the scroll case which is assumed to be "downward."

Having described our invention, what we regard as new and desire to secure by Letters Patent is:

1. In an oil burner having a motor, a blower fan driven thereby and having a discharge port, a scroll case secured to the discharge port of said fan, and a blast tube leading from said scroll case at right angles to the axis of said discharge port; a deflector mounted in the scroll case adjacent the said port, an end portion of said deflector forming an extension of said port, the surface of said deflector adjacent said port coinciding with the curvature of the scroll case, the opposite surface being curved on a radius greater than that of the blast tube, and at least one side of said deflector comprising a plane surface extending from the end portion thereof adjacent the said port to the opposite end of the deflector.

2. In an oil burner having a motor, a blower fan driven thereby and having a discharge port, a scroll case secured to the discharge port of said fan in such manner that the air stream leaving said discharge port enters said scroll case substantially tangentially thereof, and is thus given a rotary motion therein, and a blast tube leading from said scroll case at right angles to the axis of said discharge port; a deflector mounted in the scroll case adjacent the said port and having a projection thereon adapted to prevent the air stream from said port passing directly into the blast tube, and a portion extending into said scroll case in the path of the air stream rotating therein to reduce the rotation of the air stream.

3. In an oil burner having a motor, a blower fan driven thereby and having a discharge port, a scroll case secured to the discharge port of said fan in such manner that the air stream leaving said discharge port enters said scroll case substantially tangentially thereof, and is thus given a rotary motion therein, and a blast tube leading from said scroll case at right angles to the axis of said discharge port; a deflector comprising a pair of angularly disposed plane surfaces united by a pair of intersecting cylindrical surfaces extending at right angles to at least one of said plane surfaces, the several sur-

faces converging at one end of the deflector to a common point, the other end of the deflector being cut away to form a cylindrical surface of radius equal to that of said discharge port; said deflector being mounted in said scroll case adjacent said port with the last named cylindrical surface forming a continuation of said port, and with one plane surface at right angles to said first named cylindrical surfaces in contact with the side of the scroll case opposite the blast tube, whereby the other of said plane surfaces forms a deflecting surface adapted to reduce the rotation of the air stream in said scroll case and direct it toward said blast tube.

4. In an oil burner having a motor, a blower fan driven thereby and having a discharge port, a scroll case secured to the discharge port of said fan in such manner that the air stream leaving said discharge port enters said scroll case substantially tangentially thereof, and is thus given a rotary motion therein, and a blast tube leading from said scroll case at right angles to the axis of said discharge port; a deflector comprising a pair of angularly disposed plane surfaces united by a pair of intersecting cylindrical surfaces extending at right angles to at least one of said plane surfaces, the several surfaces converging at one end of the deflector to a common point, the other end of the deflector being cut away to form a cylindrical surface of radius equal to that of said discharge port; said deflector being mounted in said scroll case adjacent said port with the last named cylindrical surface forming a continuation of said port and constituting a baffle preventing the air stream from said port passing directly into the blast tube, and with one plane surface at right angles to said first named cylindrical surfaces in contact with the side of the scroll case opposite the blast tube, whereby the other of said plane surfaces forms a deflecting surface adapted to reduce the rotation of the air stream in said scroll case and direct it toward said blast tube.

5. In an oil burner having a motor, a blower fan driven thereby and having a discharge port, a scroll case secured to the discharge port of said fan in such manner that the air stream leaving said discharge port enters said scroll case substantially tangentially thereof, and is thus given a rotary motion therein, and a blast tube leading from said scroll case at right angles to the axis of said discharge port; a deflector having a surface curved on the same radius as that of said discharge port and a plane surface; said deflector being mounted in said scroll case adjacent said port with the curved surface forming a continuation of said port and constituting a baffle preventing the air stream from said port passing directly into the blast tube, and with the plane surface extending into said scroll case in the path of the air stream rotating therein so as to form a deflecting surface adapted to reduce the rotation of said air stream and direct it toward said blast tube.
